UNITED STATES PATENT OFFICE.

ROBERT T. WALTON AND JOHN E. MACDONALD, OF PHILADELPHIA, PENNSYLVANIA.

CASTER.

1,367,335.

Specification of Letters Patent.

Patented Feb. 1, 1921.

Application filed August 27, 1920. Serial No. 406,328.

To all whom it may concern:

Be it known that we, ROBERT T. WALTON and JOHN E. MACDONALD, citizens of the United States, residing in the city and county of Philadelphia, State of Pennsylvania, have invented a new and useful Caster, of which the following is a specification.

Our invention consists of a caster in which provision is made for adjusting the height of the same relatively to the leg, foot or base of a piece of furniture, or other article, and for leveling the caster relatively to the floor on which the roller runs, to which the caster is applied, and further of the provision for retaining the pintle of the caster in said leg, foot or base without liability to drop therefrom, but which is removable when so required.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation of a caster embodying our invention, and a vertical section of a leg of a piece of furniture to which it is applied.

Fig. 2 represents a vertical section thereof on line 2—2 Fig. 1.

Fig. 3 represents a side elevation of the caster certain portions having been removed therefrom.

Fig. 4 represents a perspective view of a thimble employed.

Fig. 5 represents a perspective view of a bushing employed.

Similar numerals of reference indicate corresponding parts in the figures.

Referring to the drawings,

1 designates the roller of the caster, 2 the ears on which the axle 3 of the same is mounted, 4 the pintle which is connected at its bottom with the crown portion or connecting plate 5 of said ears, its upper portion being adapted to enter the leg 4* (or other portion of a piece of furniture) or other article to which the caster is applied.

On the portion of the pintle 4 above the crown 5 is the channel plate 6 forming a race to receive the balls 7 which are adapted to roll on the crown 5 and are retained thereon by said plate 6, thus providing ball

bearings for the contiguous parts, and which of themselves are known in the art.

The spindle 4 has thereon screw-threads 8 with which engages the follower or nut-like member 9, the same being adapted to be screwed up or down on said spindle for leveling purposes.

10 designates a base plate which has thereon upwardly extending teeth 11, it being adapted to have the bottom of the leg 4* seated on it, and said teeth being adapted to be driven into or engage said bottom, thus connecting said plate with said leg, said base having centrally therein an opening to allow the pintle 4 to pass freely therethrough, it being noticed that said plate 10 rests on said follower, and so it may be raised and lowered by the latter on the pintle.

Rising from the center of the base is the tubular thimble 12 which freely encircles the pintle 4, and may be raised and lowered with the plate 10 for primarily adjusting the height of said thimble, it being noticed that on the upper end of the latter is the conical head 13 and that said thimble is conical in form, its diameter at the top being somewhat less than the diameter of the pintle and considerably less than the diameter of the head 13, consequently the pintle cannot drop through said thimble and from the leg 4* and so the caster retains its connection with the latter.

In order to render the thimble resilient whereby it may be expanded, the upper portion of the side is cut through forming 90 the tapering slits 14 which divide the said upper portion and permit the latter to spread apart whereby when the spindle is inserted into the thimble, the head 13 expands the upper narrow portion of the 95 thimble and so said head is caused to pass through said portion. Then when the head 13 clears the top edge of the thimble, the upper narrow portion of the latter contracts and springs under the head 13, the head then 100 overhanging the top edge of the thimble, whereby said head is prevented from re-entering the spindle and dropping from the same, and displacement of the caster from the leg 4* thus being prevented.

Should it be desired to remove the caster, superior force may be applied to the same to draw out the pintle from the thimble, when the conical head 13 rides down into the top of the thimble and spreads apart 110

the divided walls thereof and so said head and the pintle may slide through the thimble and the base plate 10 and be removed thereby from the latter, the caster thus being detached from the leg.

To prevent the threads of the pintle engaging the inner bore of the thimble there is placed within the latter the unthreaded sleeve 15 which encircles freely the pintle 10 as a bushing and is encircled freely by the thimble, and so the pintle has the greatest freedom of rotary motion in the leg 4* as the roller of the caster performs its operations.

The sleeve or bushing 15 rests on the following lower 9 and so follows the adjustment of the thimble up or down.

The thimble is not necessarily conical throughout its entire length, so the lower portion thereof may be cylindrical so as to fit snugly in the bore of the leg to hold it steady and without wobbling therein.

Having thus described our invention what we claim as new and desire to secure by Letters Patent, is:—

1. In a caster, a roller, a bearing for the latter, a threaded pintle connected with said bearings and rising therefrom and having a conical head, a follower on said pintle, a conical thimble adapted to freely encircle a portion of said pintle and to be engaged by

said follower whereby said thimble may be adjusted vertically by said follower, said thimble being adapted to be retained freely on said pintle.

2. In a caster, a roller, a bearing for the latter, a pintle connected with said bearing and having a conical head, and a thimble adapted to encircle said pintle freely, said thimble being adapted to contract on said pintle below said head and connect the thimble freely therewith and to expand to permit the introduction of the pintle into said thimble and to permit it to be removed therefrom.

3. In a caster, a roller, a bearing for the latter, a threaded pintle connectible with said bearing, a thimble adapted to encircle freely said pintle, a bushing interposed between said pintle and thimble to prevent engagement of the threads of the former with the bore of the latter, and a follower on said pintle adapted to adjust said thimble in height and against which said thimble and bushing rest.

ROBERT T. WALTON.
JOHN E. MACDONALD.
